UNITED STATES PATENT OFFICE.

CHARLES H. CARLSON, OF MINNEAPOLIS, MINNESOTA.

ELECTRIC WATER HEATER.

Application filed August 29, 1921. Serial No. 496,233.

To all whom it may concern:

Be it known that I, CHARLES H. CARLSON, a subject of the King of Sweden, residing at Minneapolis, in the county of Hennepin and 5 State of Minnesota, have invented certain new and useful Improvements in Electric Water Heaters, of which the following is a specification.

My invention relates to electric water heaters, and an object is to provide a device of 10 this character which may be conveniently placed in a water supply pipe so as to heat the water passing therethrough.

The full objects and advantages of my 15 invention will appear in connection with the detailed description, and the novel features embodied in my invention idea are particularly pointed out in the claims.

In the accompanying drawings which 20 illustrate one of the embodiments which my invention may assume, Fig. 1 is an elevational view of my electric heater. Fig. 2 is a view showing the heater in longitudinal section and the electrical connections dia- 25 grammatically. Fig. 3 is a view in section on the line 3—3 of Fig. 2. Fig. 4 is a view in section on the line 4—4 of Fig. 2.

As shown in the drawings my heater is 30 connected to the pipes 10 and 12 of any suitable or customary water supply system, the pipe 10 being the inlet pipe to the heater and the pipe 12 being the outlet from the heater. The pipes 10 and 12 are coupled together by a pipe section 14. Lying within 35 the section 14 and spaced from the inner wall thereof is a copper shell 16 which has a closed end 18. The opposite end of this shell is shown with an enlarged portion 19 which is threaded at 20 into the section 14, while the extreme end of this enlarged portion is threaded into a metallic sleeve 22. The shell 16 when in place is airtight and air is exhausted from the same. Lying within 40 the shell 16 and spaced from the inner wall thereof is a carbon rod 24, one end of which rests against the end 18 of the shell, and the other end of which is held in a socket formed in a metallic rod 26 which is 45 slidably mounted in bushings 28 and 30 of insulating material. A coiled spring 32 surrounding the rod 26 between the bushings 28 and 30 serves to maintain the free end of the carbon rod 24 in contact with the closed 50 end 18 of the copper shell. A wire 34 is connected to a lug 35 on the sleeve 22 and a wire 36 is connected to the outer end of the

rod 26 by a clamp 38 and the connections of these wires are protected by a fiber sleeve 40 secured to and extending out from the sleeve 22. The outer ends of the wires 34 60 and 36 are connected to a transformer coil 42, the other coil 44 of the transformer joining wires 46 and 48 which supply current from any suitable source of electrical energy. By means of the transformer, the voltage of 65 the supply current may be greatly reduced. A switch 50 may be placed at any desired place in the circuit of the wires 46 and 48.

The operation and advantages of my invention will be obvious from the foregoing 70 description. My heater may be installed at any convenient place in the supply pipe of a water system. When the switch 50 is closed, the reduced current from the transformer passes from the wire 36 through the 75 rod 26 to the carbon rod 24 which is highly heated thereby and, hence, heats up the copper shell 16 through which the current returns to the wire 34. Water entering the heater through the pipe 10 passes around 80 the shell 16 by means of which it is quickly heated and the hot water flows out through the pipe 12 to the desired place where it is to be used.

I claim:

1. An electric water heater comprising a 85 pipe section adapted to be placed in a water supply pipe, a metallic shell spaced within said pipe section, a carbon rod spaced within said shell and having one end in contact therewith, and an electrical circuit connected with said carbon rod and said shell.

2. An electric water heater comprising a 90 pipe section adapted to be placed in a water supply pipe, a metallic shell spaced within said pipe section, a carbon rod spaced within said shell, resilient means for holding an end of said carbon rod in contact with said shell, and an electrical circuit connected with said carbon rod and said shell.

3. An electric water heater comprising a 95 pipe section adapted to be placed in a water supply pipe, a metallic shell spaced within said pipe section and having one of its ends closed and its other end secured to said shell, a carbon rod spaced within said shell, a spring for holding one end of said carbon rod in contact with said closed end, and an electrical circuit connected with said carbon rod and said shell.

4. An electric water heater comprising a 100 pipe section adapted to be placed in a water
